STAR-DISK ROLLER BIT

John A. Zublin, Los Angeles, Calif.

Application August 29, 1938, Serial No. 227,280

7 Claims. (CL 255—71)

This invention relates to drilling tools, and more particularly to that class of tools that is used in the rotary drilling of wells, and still more specifically to the type of drilling tools described in my United States Patents Nos. 2,050,988, 2,050,989, 2,069,795, 2,069,796, 2,069,797, 2,069,798, 2,069,799, 2,079,142, 2,118,542 and 2,126,079; and in many of my United States applications.

Specifically, the present invention is more closely related with the applications referred to. In Patent No. 2,126,079, the invention described therein is concerned with the use of disks which are in rolling contact with the formation, being especially adaptable for making efficient drilling progress in hard formations. Although the extent of penetration of each disk is greater than is obtainable with corresponding star rollers, under some conditions of operation the disks do not turn freely about their own respective axes. This is probably due to the fact that the turning force of engagement between the disks and the formation is of insufficient magnitude to overcome the bearing friction between each roller and its supporting pin. Especially does this occur when a plain friction type of bearing is used. As a consequence of the inability of the disks to turn freely on their bearing supporting pins, their cutting edges will slide over the formation and become flattened. This will provide additional resistance to the turning of the cutters about their own respective axes since the flattening will introduce an additional sliding of the disk upon the formation preventing its rolling action in the manner intended and aggravating the flattened condition.

It is further desirable that the disks be maintained free from cuttings in order that they can penetrate the formation without being impeded by detritus caked on and between their cutting edges. In my Patent No. 2,118,542, an inclined upper nozzle is both described and claimed having among its purposes the rotation of the cutters as they move into the line of action of the fluid issuing from the nozzle. When star rollers are used, the fluid stream can impinge upon the cutting teeth in much the same manner as water can act upon the buckets of a water wheel, and due to its impact with the teeth, cause rotation of the rollers. However, in using disk rollers, the turning effort of the fluid stream upon the disks is limited to the friction of the fluid as it encounters the side faces of the disks. This force is probably insufficient in producing rotation of the disks so that all of their cutting edges are

not acted upon by the fluid stream as each roller passes under it.

In its essential aspects the present invention is concerned with overcoming the above noted difficulties. Accordingly, it becomes an object of this invention to insure rotation of the disks while they are in contact with the formation, thus preventing flattening of their cutting edges and obtaining uniform wear thereon so that during the effective life of the drilling tool the cutting edges of each disk will be substantially equidistant from the axis of the cutter.

A further object of the invention is to provide instrumentalities operable in conjunction with disks to insure thorough cleaning of the disks by virtue of their rotation by fluid issuing from a cleaning nozzle.

A further object of the invention resides in the provision of a composite roller, preferably including both disks and teeth, which will conform to the outline produced on the hole bottom and which will insure rotation of the disks while they are in contact with the formation.

How these objects and others are obtainable will be understood by reference to the following description and the annexed drawing, in which:

Figure 1 is a partial section on the line 1—1 of Figure 2; and

Figure 2 is a partial section on the line 2—2 of Figure 1.

In its general aspects, the invention contemplates the use of rolling disk cutters which will produce a more effective breakdown of the formation than roller cutters having teeth over their entire earth contacting portions. The advantages of using disks have been described in my application entitled "Rolling disk bits". The present invention contemplates taking the benefits associated with rolling disks while overcoming their disadvantages. In furtherance of this end, each roller is a composite of a disk and a star roller, the teeth on the star portions in effect gearing themselves to the formation so that the entire roller is caused to rotate about its own axis at all times while in formation contact, thereby overcoming the tendency of the disks to be arrested by virtue of the bearing friction between it and its supporting pin. Furthermore, fluid issuing from a cleaning nozzle will first engage against the teeth on the star portions of the roller, causing the roller to rotate and by the kinetic energy stored therein the roller will continue to rotate while the disk portions pass under the fluid stream. In this manner there is assurance that the entire cutting surface on each

disk will be acted upon and cleaned by the fluid stream.

The specific embodiment of the invention disclosed on the drawing is of a drill bit provided with a shank 10 having on its upper end a threaded portion 11 by means of which the shank is attached to a drilling string for rotation about a generally longitudinal axis A—A. The lower portion of the shank is equipped with two depending legs 12 carrying between them the cutter carrier 13. About the periphery of the cutter carrier is rotatably mounted a plurality of roller cutters 14 comprising disk portion 14a and toothed star portions 14b.

As described in my Patent No. 2,079,142, the carrier is rotatably mounted between the shank legs by means of bearing member 15 which consists of a central cylindrical sleeve 16 and flanges 17 screwed into each end of the bearing sleeve. The carrier has an inner cylindrical surface 18 rotatably mounted on the sleeve, and inclined surfaces 19 complementary to the flanges. Between the flanges and these inclined surfaces are ball bearings 20 which serve to transmit part of the radial load on the carrier and all of the axially parallel loads.

On the outer surface of each flange is provided a raised boss 21 which is inserted into a transverse slot 22 formed in each of the legs of the shank. The bosses are flattened across their top and bottom sides 23, 24 in order that they can be slid into the slots in the legs and be held from rotating relatively thereto. Relative rotation between the flanges is prevented by means of a locking pin 25. The entire assembly is attached to the legs of the shank and held in proper position by tapered pins 26 which are externally threaded at 27, cooperating threads being supplied in each flange. Removal of the tapered pins is prevented by inserting cotter keys 28 through a bore 29 in each pin, the legs of each pin being bent back to engage with castellations 30 in each pin and with slots 31 in the shank.

To lubricate the bearing surfaces, passageways 32 for the circulating fluid are supplied at intervals around the carrier. These passageways will convey the fluid from each roller cutter to the bearing surface.

As explained in my Patents Nos. 2,050,988 and 2,069,799, a drilling tool of the type just described will have its cutters brought "intermittently" into and out of contact with the formation being operated upon. Thus, each cutter has three degrees of freedom of motion, namely, revolution about the axis A—A of the hole, revolution about the inclined axis B—B of the carrier, and rotation about its own axis, which is the axis of the pins 31 directly supporting each cutter. Each cutter will trace a generally spiral path upon a concave or hemispherical bottom of the hole produced by drill bits of this type. This is due primarily to the combined rotation of the shank and the movement of the carrier 13 about its own axis B—B, which latter motion produces the "intermittent" contact of the roller cutters, above referred to. Because of this type of motion, each cutter will be moved successively out of contact with the formation and will be positioned under a fluid nozzle 34 threaded into the shank and communicating with the fluid passage 33 contained therein.

It will be noted that each composite roller is mounted on the carrier so that its star portion 14b is positioned ahead of the disk portion 14a as regards carrier rotation. As seen in Figure 1, the

carrier will rotate in a clockwise direction to place the star roller portion 14b in the line of action of the fluid stream issuing from the nozzle 34. Such line of action is to one side of the axis of each roller, the fluid impinging upon the cutting teeth of the star portion 14b, cleaning them and also rotating the roller so that all parts of the star are thoroughly flushed by the fluid. The rotation of the roller thus initiated will continue as the disk portion 14a passes under the stream. The fluid will operate upon each disk on the roller and will tend to continue rotation of the roller because of the friction of the fluid against the side faces of each disk. The arrangement shown and described thereby provides assurance that all parts of the composite roller will be maintained free from cuttings.

As was indicated above, the bearing friction between the rollers and their supporting pins 31 might in some instances be sufficient to arrest rotation of the roller on the pin and result in a sliding action of the disks on the formation and their consequent flattening. However, the toothed star portion 14b of each roller will contact with the formation and become functionally geared thereto while moving in its spiral path along the hole bottom. In this respect, positioning the star in advance of the disk portions as regards the direction of carrier rotation possesses an additional advantage that it is this portion which will come into engagement with the formation first, causing it to rotate almost immediately and eliminating any tendency of the disk to slide on the formation or to become arrested prior to a subsequent engagement of the star roller portion, which might occur were the tooth portion positioned rearwardly of the disks as regards carrier rotation.

Although in Figure 1 all of the star portions have been shown as being positioned ahead of the disk portions as regards carrier rotation, to eliminate any tendency towards tracking, the disk portions might be positioned ahead of the star portions on only some of the rollers. Alternate rollers can have their star portions positioned before the disks, the other rollers having disk portions ahead of the star portions. It will be noted further that the teeth on the star portion can be shaped to extend parallel to the roller axis or they can be inclined with respect thereto, as by forming them generally like helical gear teeth. Also each disk may extend perpendicularly with the roller axis or it can make an angle therewith as by forming the disk like a helical thread of relatively steep pitch, or of cup shape.

To maintain all of the disks on each cutter and the star teeth in substantially simultaneous contact with the formation, each roller cutter is shaped to conform to the generally hemispherical surface produced at the bottom of the hole. This is accomplished by shaping each cutter with its disk edges and the star tooth ends lying on a surface of barrel shape, the curvature of the surface having substantially the same radius as the radius of the hemispherical hole bottom. The drilling tool is thereby attended with a smooth operation.

The drilling tool described combines the advantages of disks, as regards their ability to cut certain types of formations that cannot be effectively penetrated by rollers toothed along their entire formation contacting portions, and of star rollers, which can remove other types of formation effectively by an impact action. This makes the tool more nearly universal in its application.

to the making of holes in various types of hard formation, in addition to eliminating the disadvantages associated with drilling tools using disks entirely and those using star rollers entirely.

It will be understood that my invention may be embodied in various forms and that the specific illustration on the drawing is to be construed as an example of the invention rather than as imparting any limitations thereon; and that various changes can be made without departing from the invention so long as they fall within the scope of the claims appended hereto.

I claim:

1. An earth boring tool comprising a shank, one or more rollers rotatable with respect to said shank, and means mounting said rollers on said shank for intermittent contact with the formation, at least one of said rollers having disk cutters with continuous circumferential cutting edges on a portion thereof and toothed cutters on another portion thereof.

2. An earth boring tool comprising a shank, a cutter carrier rotatably mounted on said shank, and a plurality of rollers rotatably mounted on said carrier, each roller having disk cutters with continuous circumferential cutting edges on a portion thereof and toothed cutters on another portion thereof in advance of said disk cutters as regards the direction of carrier rotation on said shank.

3. An earth boring tool comprising a shank, a cutter carrier rotatably mounted on said shank, and a plurality of rollers rotatably mounted on said carrier, each roller having one or more disk cutters on a circumferential portion thereof and toothed cutters on another circumferential portion thereof in advance of said disk cutters as regards the direction of carrier rotation on said shank.

4. An earth boring tool comprising a shank, a cutter carrier rotatably mounted on said shank,

a plurality of rollers rotatably mounted on said carrier, and fluid means on the shank adapted to effect a cleaning of the rollers, each roller having one or more disk cutters on a portion thereof and tooth cutters on another portion thereof in advance of said disk cutters as regards the direction of carrier rotation on said shank, whereby by said toothed cutters will be acted upon by fluid issuing from said fluid means prior to said disk cutters to rotate and clean the roller cutting portions.

5. An earth boring tool comprising a shank, a cutter carrier rotatably mounted on said shank, a plurality of rollers rotatably mounted on said carrier, and fluid means on the shank adapted to effect a cleaning of the rollers, each roller having one or more disk cutters on a circumferential portion thereof and toothed cutters on another circumferential portion thereof in advance of said disk cutters as regards the direction of carrier rotation on said shank, whereby said toothed cutters will be acted upon by fluid issuing from said fluid means prior to said disk cutters to rotate and clean the roller cutting portions.

6. An earth boring tool comprising a shank, one or more rollers rotatable with respect to said shank, and means mounting said rollers on said shank for bodily translation with respect to said shank, at least one of said rollers having disk cutters on a circumferential portion thereof and toothed cutters on another circumferential portion thereof.

7. An earth boring tool comprising a shank, one or more barrel-shaped rollers rotatable with respect to said shank, and means mounting said rollers on said shank for bodily translation with respect to said shank, at least one of said rollers having disk cutters on a circumferential portion thereof and toothed portions on another circumferential portion thereof.

JOHN A. ZUBLIN.
